UNITED STATES PATENT OFFICE.

ROBERT R. DUNLOP, OF COLUMBUS, OHIO, ASSIGNOR TO THE JEFFREY MANUFACTURING COMPANY, OF COLUMBUS, OHIO, A CORPORATION OF OHIO.

ELECTRIC LOCOMOTIVE.

Application filed July 12, 1922. Serial No. 574,561.

To all whom it may concern:

Be it known that I, ROBERT R. DUNLOP, a citizen of the United States, residing at Columbus, in the county of Franklin and 5 State of Ohio, have invented certain new and useful Improvements in Electric Locomotives, of which the following is a specification, reference being had therein to the accompanying drawing.

10 The present invention relates to certain new and useful improvements in electric locomotives, and particularly to locomotives of the class which is adapted to use in the restricted passages of coal mines and similar underground workings.

15 In electric cars, such as are commonly employed in interurban and street railway service, the grid resistance elements which form a part of the motor controlling mechanism, 20 are commonly mounted upon the under side of the car floor in position to be conveniently inspected and repaired.

25 Locomotives designed for service in the restricted passages, and under the trying conditions of service in coal mines, are necessarily much more compact than are similar vehicles designed for use above ground, and the auxiliary devices necessary to the manipulation of these locomotives 30 must be more fully protected from mechanical injury than is necessary above ground. In mine locomotives it has heretofore been customary to mount such devices inside the frame of the locomotive in comparatively 35 inaccessible positions.

40 It is the especial object of this invention to provide improved mountings for the electrical resistance elements of coal mine locomotives whereby said elements will be fully protected from mechanical injury and will be conveniently accessible for inspection and repair.

45 The devices by which I attain this object are fully disclosed in the following specification reference being had to the accompanying drawings of which,

Fig. 1 is a perspective view of an electric locomotive equipped with the devices of my invention.

50 Fig. 2 is a fragmentary vertical cross section taken along the line II—II of Fig. 1.

Fig. 3 is a fragmentary horizontal section taken along the line III—III of Fig. 2.

55 Fig. 4 is a view similar to Fig. 3 showing the door of the resistance compartment

partly open to disclose the included resistance element.

Like numerals refer to similar parts in the several figures.

In Fig. 1 of the drawings I have shown 60 an electric locomotive, especially designed for service in coal mines, comprising a main frame 1 which is built up of suitable structural steel plates and shapes, and within which are mounted the electric motors, not 65 shown in the drawings, by which the locomotive is actuated. The frame 1 is mounted upon driving wheels 2 adapted to travel along the rails 3 of the mine track, and which are secured to the locomotive frame, 70 and connected by suitable gearing with the electric motors, in the manner well understood in the art. Electric current for the actuation of the electric motors is derived from the trolley wire 4 through the trolley 75 pole 5 and is controlled by a suitable controller 6 positioned within convenient reach of the operator, and by suitable electric resistance elements 7 connected therewith. As 80 these devices are well understood in the art, and as they form no part in the present invention, further illustration and description of them is not thought to be required at this time.

The locomotive frame 1 comprises the side 85 sills 8 and the end sills 9 which are formed of suitable channel bars securely joined together by the angle blocks 10 and braced by the floor plates 11 in the manner common in locomotive practice. To the end sills 9 are 90 secured bumper blocks 12 having draw pockets 13 adapted to engage the coupling links by which the locomotive is connected with its load. Sand boxes 14 attached to the side sills 8 are arranged to deliver sand through 95 the spouts 15 to the track rails 3 adjacent the wheels 2. The end sills 9 and the floor plates 11 project laterally beyond the side sills 8, and the spaces included between the projecting ends of the sills 9 and the sand 100 boxes 14 are roofed over by plates 16 secured to the side sills 8 to form chambers in which the resistance elements 7 are mounted. Cover plates 17 connected to the locomotive frame by hinges 18, are arranged 105 to close the resistance chambers and to protect the included resistance elements from mechanical injury. The resistance elements 7 may be of any preferred type, but are here illustrated as of the well known multiple 110

grid type, and are securely bolted to and swing with the cover plate 17. The electric conductor cables 19 afford such flexibility of connection that the cover plate 17, together with the resistance elements 7, may be swung to the open position without disturbing the electrical connections of the resistance. Cap screws 20 extending through apertures in the cover plates 17 and screw threaded into bosses of the sand boxes 14, as shown in Fig. 3, serve to retain said cover plates in closed position.

By the arrangement of parts above described the resistance elements 7 are securely mounted upon the frame of the locomotive, protected from accidental contact with external objects, and are adapted to be expeditiously moved to positions convenient for inspection and repair without disturbing the electrical connections of the locomotive.

I claim:

1. In an electric locomotive of the class described, the combination with a locomotive frame, of a compartment formed in said frame, a cover plate hinged to said frame and adapted to close said compartment, and an electric resistance element flexibly connected with the electric circuits of the locomotive normally positioned within said compartment and rigidly attached to and movable with said cover plate as and for the purpose set forth.

2. In an electric locomotive of the class described, the combination with a locomotive frame, of a plurality of compartments formed in said frame, cover plates hinged to said frame and adapted to close said compartments, and electric resistance elements flexibly connected with the electric circuits of the locomotive normally positioned within said compartments and rigidly attached to and movable with said cover plates as and for the purpose set forth.

3. In an electric locomotive of the class described, the combination with a locomotive frame, of an outwardly opening compartment formed in said frame, a cover plate hinged to said frame and adapted to close said compartment, and an electric resistance element flexibly connected with the electric circuits of the locomotive normally positioned within said compartment

and rigidly attached to and movable with said cover plate as and for the purpose set forth.

55

4. In an electric locomotive of the class described, the combination with a locomotive frame of a member hinged to said frame, and an electric resistance element flexibly connected with the electric circuits of the locomotive and rigidly attached to and movable with said hinged member as and for the purpose set forth.

5. In an electric locomotive of the class described, the combination with a locomotive frame, of a compartment formed in said frame, an electric resistance element mounted within said compartment and connected with the electric circuits of the locomotive, and a plate hinged to said locomotive frame and adapted to protect said resistance element from contact with objects external of the locomotive.

6. In an electric locomotive of the class described, the combination with a locomotive frame, of a compartment within said frame, a cover plate hinged to said frame and adapted to close said compartment, and an electric resistance element connected with the electric circuits of the locomotive positioned within said compartment and rigidly attached to said hinged plate as and for the purpose set forth.

7. In an electric locomotive of the class described, the combination with a locomotive frame, of a member hinged to said frame, an electric resistance element flexibly connected with the electric circuits of the locomotive and mounted upon and movable with said member as and for the purpose set forth.

8. In an electric locomotive of the class described, the combination with a locomotive frame, of a compartment within said frame, a cover plate adapted to close said compartment, and an electric resistance element normally positioned within said compartment flexibly connected with the electric circuit of the locomotive and mounted upon and movable with said cover plate as and for the purpose set forth.

In testimony whereof, I affix my signature.

ROBERT R. DUNLOP.
